SHUTTLE FOR CIRCULAR LOOMS

Frederick Sutton Hardy, Spondon, near Derby, England, assignor to Celanese Corporation of America, a corporation of Delaware

Application October 11, 1938, Serial No. 234,338
In Great Britain October 25, 1937

3 Claims. (Cl. 139—13)

This invention relates to the shuttles of a circular loom of the kind in which the weft is carried by a flat spool or cheese held stationary in the shuttle body. The invention is particularly concerned with means for removable securing the weft package in position.

According to the invention, a weft package with a flat flange is held in the shuttle body by means that engage the flange, these means comprising at least three hooked catches behind which the flange may be slid, the catches making engagement with points widely spaced round the periphery of the flange, and spring means adapted to engage the flange so as to keep the flange firmly behind the catches.

The catches are preferably so arranged that the flange is held by the catches flat against a supporting plate in the shuttle, so that the utmost space is left available for the thickness 20 of the package in order to accommodate the maximum amount of weft in the relatively thin shuttle that the restricted shed opening in a circular loom permits, it being understood that the supporting plate lies as closely as possible 25 to one sheet of warps and that the thickness of the package is such that at the side of the shuttle remote from the supporting plate the package lies just clear of the other sheet of warps.

30 The invention will now be described in greater detail with reference to the accompanying drawing showing a package mounting arrangement having three catches for engaging the flange of the package, and spring means independent of the foremost catch to urge the flange behind the rearmost catches.

In the drawing

Fig. 1 is a front elevation of the upper part of a shuttle showing the weft package mounted 40 in position;

Fig. 2 is a part sectional plan taken on the line 2—2 of Fig. 1;

Fig. 3 is a part sectional plan taken on the line 3—3 of Fig. 1, but on a larger scale; and

45 Fig. 4 shows the complete shuttle to a smaller scale.

The shuttle comprises a body 1 carrying flanged rollers 2 at two different levels, and a roller 3 freely mounted on a substantially vertical axis, the rollers 2 and 3 serving for the positioning and driving of the shuttle. Below the body 1 is a plate terminating in a beat-up edge 4, provided with alternative weft eyes 5, 6. Above the body 1 are plates 7, 8, shaped so as to 50 permit the smooth passage of the shuttle through

the shed, and the forward part of the shuttle carries a warp feeler device 9. The plates 7, 8 are connected by plate members 10, 11, against which the flange 12 of the weft package 13 is to rest, as shown in Fig. 2.

The rear plate 11 has a pair of hooks 14 formed to engage the flange 12 at two points lying respectively above and below the axis of the package. The forward plate 10 is bent at right angles so as to impart rigidity to the whole structure above the plate 7, and the portion 15 of the plate 10 carries a pin 16 behind which the flange 12 can fit snugly. The pin 16 is at the level of the axis of the package. In addition, the member 10 has riveted to it at points 17 a flat spring 18, the free ends of which are bent as shown at 19, to receive pins 20, 21 passed through slots 22 in the plate 10. The pins are soldered to the spring 18, and are urged by the spring towards the hooks 14.

When a weft package is to be inserted in the shuttle, its flange 12 is pressed against the pins 20, 21 and behind the pin 16 until its right hand edge can rest against the plate 11. The spring 18 then urges the flange 12 behind the hooks 14, the hooks 14 and pin 16 then serving as catches to prevent the flange from being lifted away from the plates 10, 11. The pin 16 is long enough to maintain contact with the flange after the flange has been pushed rearward behind the hooks 14.

The pins 20, 21 are bent at right angles, as shown at 23 in Fig. 3, so as to maintain between the spring 18 and the plate 10 a space just sufficient for the passage of the flange 12 into engagement with the pins 20, 21, and to prevent the spring and the pins from moving away from the plate far enough to miss engaging the flange. The curve formed by bending the pins into the portion 23 offers no obstruction to the passage 40 of the warps over that side of the shuttle, and the flange 12 being held close against the plates 10, 11, substantially the whole thickness of the shuttle from front to back is available for weft 45 on the package 13.

To remove a weft package, the flange 12 is pushed against the spring 18 until its rear edge clears the hooks 14; the flange is then lifted away from the plate 11 and drawn clear of the pin 16. Removal and replacement of the package 50 can thus be effected very quickly, and yet the package is held firmly in place in the shuttles.

Having described my invention, what I desire to secure by Letters Patent is:

1. A circular loom shuttle comprising at least

three catches behind which the flange of a removable weft spool may be slid, two of said catches being disposed to engage on one side of a vertical line through the shuttle and one catch 5 engaging on the other side of said vertical line so that said catches make engagement at points widely spaced round the periphery of the flange, and spring means adapted to engage the flange and urge the flange firmly behind the two catches 10 on one side of said vertical line.

2. A circular loom shuttle comprising at least three catches behind which the flange of a removable weft spool may be slid, two of said catches being disposed to engage on one side of a 15 vertical line through the shuttle and one catch engaging on the other side of said vertical line so that said catches make engagement at points widely spaced round the periphery of the flange,

and spring means adapted to engage the flange and urge the flange firmly behind the two catches on one side of said vertical line, said spring means being independent of said catches.

3. A circular loom shuttle comprising at least 5 three catches behind which the flange of a removable weft spool may be slid, the catches making engagement at points widely spaced round the periphery of the flange, two of said catches being disposed to engage the rear edge of 10 the flange and one catch to engage the front edge of the flange, and spring means adapted to engage the flange and urge it behind the two rearmost catches so as to keep the flange firmly behind the catches, said spring means making 15 contact with two points on the periphery of the flange.

FREDERICK SUTTON HARDY.
